(57) **CLAIM**

The ornamental design for a combined cylindrical pile, sheet pile, and connecting element, as shown and described.

DESCRIPTION

FIG. 1 is a bottom and right side perspective view of a combined cylindrical pile, sheet pile, and connecting element.

FIG. 2 is a top side plan view thereof of the embodiment depicted in FIG. 1;

FIG. 3 is a bottom side plan view thereof of the embodiment depicted in FIG. 1;

FIG. 4 is a rear elevational view thereof of the embodiment depicted in FIG. 1;

FIG. 5 is a front elevational view thereof of the embodiment depicted in FIG. 1;

FIG. 6 is a left side elevational view thereof of the embodiment depicted in FIG. 1; and,

FIG. 7 is a right side elevational view thereof of the embodiment depicted in FIG. 1.

1 Claim, 4 Drawing Sheets
